PUMP

Frank J. Miller, Santa Monica, Calif.

Application September 16, 1937, Serial No. 164,897

6 Claims. (Cl. 166—20)

The invention relates to pumps for use in deep wells for raising liquids, such as oil and water therefrom.

The invention pertains particularly to attachments for pumps of this character which allow the strainer and the adjacent formation to be cleaned while the pump is operating.

It is one of the objects of the invention to provide a pump having a reciprocating plunger 10 therein with means associated therewith to force liquid through the strainer to clear the openings therein and to carry the foreign material upwardly so that it may be discharged at the surface.

15 I desire to provide means associated with the pumping apparatus to pack off portions of the strainer in which the pump is located and to force a current of fluid through the openings at a plurality of stages along the length of the strainer.

20 The invention consists particularly in the construction of the apparatus which will be better understood from the description which follows:

25 Referring to the drawing, Fig. 1 is a central longitudinal section through a portion of the pump and the strainer equipped with one form of my invention.

Fig. 2 is a transverse section on the plane 2—2 of Fig. 1.

Fig. 3 is a transverse section on the plane 3—3 of Fig. 1.

30 While it is possible to operate my invention in connection with many types of ordinary reciprocating pumps I have disclosed the invention as applied to a pump such as is ordinarily termed a fluid packed pump. It is to be understood, however, that the use of my invention is not confined to this particular type of pump.

35 In the drawing I have shown the pump tubing 1 as concentric with an outer perforated pipe or strainer 2 and it is to be understood that the strainer acts to prevent the entrance of sand and other material from the formation to the interior of the well.

The pump tubing 1, as shown in the drawing, 40 is connected by means of a coupling 3 to the pump barrel 4, which is threaded internally at its lower end at 5 for connection with the bushing 6 which forms a base at the lower end of the barrel.

45 The base 6 is connected at 7 to a downward extension 8 which may be the usual gas anchor, if desired. The interior of the base 6 has a tapered seat 9 within which the standing valve assembly may be seated. The upper end of the base 50 member has an annular shoulder at 10 upon which

is supported the pump liner 11 which extends from the base upwardly against a shoulder 12 upon the coupling 3. This structure may be employed to hold the liner in place or obviously said liner may be secured in place by welding or other well known means.

5 Within the seat 9 is located the standing valve which includes a tubular member 13. On the outer surface of the member 13 are placed a series of packing rings 14, the outer surface of which is tapered downwardly. Said rings are held in place upon the tubular member by a lower ring or nut 15 screwed upon the lower end thereof. The uppermost of the packing rings contact with an outer shoulder on the tubular member 13. Above the packing rings a stationary pump barrel 16 is extended upwardly for the desired height and serves to form a space between the same and the inner wall of the liner 11. This space is adapted to receive the plunger barrel 17. 10 The standing valve barrel 16 has a plurality of perforations 18 therein which may be extended in a direction inclined upwardly and serve to allow a circulation back and forth between the interior and the exterior of the standing valve barrel 16. 15

20 Within the upper end of the tubular member 13 is fitted a valve seat 19 to receive a ball valve 20 in the usual manner. A cross pin 21 in the standing valve barrel serves to limit the upward movement of the ball valve from its seat. 25 Toward the upper end of the barrel 16 is a substantial cross pin 22 which may be employed in removing the standing valve from its seat when it is necessary to withdraw the same from the well.

25 The pump plunger is made up of the plunger barrel 17 which telescopes over the standing barrel 16 and within the pump liner as will be clearly understood. The upper end of the barrel connects with a head or bushing 23 which is in turn 40 connected with the valve cage 24 in the usual manner. Between the cage and the bushing 23 is clamped the valve seat 25 upon which the ball valve 26 is located. The upper end of the cage is formed with a threaded nipple 27 for attachment to the usual pump rod.

45 My cleaning attachment for this type of pump includes a skirt 28, which is connected with the pump tubing at a point above the pump barrel. I have shown the same as welded to the tubing 50 at 29. The upper end of the skirt has an inwardly and upwardly tapered portion 30, the body of the skirt, however, being tapered downwardly and extended to a desired level below the pump. The lower end is flared outwardly and 55

provided with an upwardly extending rim 31, which serves as an attachment for a flexible bag 32 which may be of canvas or similar tough material.

5 The lower end of the canvas packer bag is secured to the rim 31 by rivets or other similar means. At the upper end of the packer is a spring 33 which may consist of a resilient hoop of spring metal which is preferably cut at some 10 point to allow a resiliency therein. This hoop may be held in place by attachment to the skirt 28 in any desirable manner. I have shown a plurality of radial pins 34 having coiled springs 35 thereon by means of which the upper end of the bag is held resiliently outward. I do not wish to be confined to this particular support for the upper end of the bag, however, as other means may be employed.

20 Within the skirt 28 and spaced from the upper end thereof I provide a ring valve. This ring valve comprises a ring-shaped member 36, which surrounds the pump tubing and rests upon a ring 37 which is secured to the tubing and to the skirt by any desired means such as welding.

25 The upper end of the seat member 37 has a tapered groove to receive the lower side of the ring 36. There are a plurality of openings 38 through the seat ring through which fluid may pass. The valve ring 36 is held downwardly in 30 its groove to close said openings by means of a spring 39, which surrounds a stem 40 projecting downwardly from the seat and bearing at its lower end against the nut 41 upon the stem. There is a cross pin 42 which serves as a support 35 for the upper end of the spring 39. It will be seen that the passage of fluid within the skirt 28 downwardly will be prevented but a predetermined pressure on the lower side of the valve will raise the ring and allow fluid to pass upwardly. An opening 43 is provided in the tubing 40 above the pump barrel and within the skirt through which fluid may pass into the pump barrel so as to be moved upwardly with the fluid raised by the pump.

45 I desire to provide a plurality of packers along the length of the strainer and I have shown a second packer along the strainer above the one previously described. This packer is similar in construction to the one noted. It has a skirt 50 shown at 28' which is somewhat shorter than the one previously noted but carrying a packer of the same construction indicated at 32'.

In the operation of the pump the fluid will be pumped upwardly through the tubing by the reciprocation of the pump plunger in the usual 55 manner. When the flow of fluid to the well is impeded by the clogging of the openings in the strainer it will be possible to wash the said openings so that the flow to the well may be continued and this washing may take place without removing the pump. This washing is performed as follows:

Liquid is pumped downwardly within the casing and outside the pump tubing into the space 65 indicated at 45 above the packer 32'. This fluid will enter the packer bag 32' and force the same outwardly against the casing or perforated pipe and prevent the fluid from passing further in that direction. The liquid will thus be forced out 70 through the openings in the strainer and into the interior of the well outside the strainer and will pass downwardly and enter the upper openings in the strainer above the next packer. This packer in turn will be inflated and prevent the 75 progress of flushing fluid downwardly inside the

strainer and force it to pass outwardly through the openings in the strainer to the exterior thereof and it will thus pass downwardly and through the openings below the next packer and upwardly through the space therein and through an opening 43 to the tubing where it will be carried upwardly with the fluid being pumped. 5

It will be obvious that this operation will not interfere with the action of the pump itself. The strainer may be freed of material therein through 10 the circulation of flushing liquid and material picked up by the flushing liquid will be carried outwardly with the fluid being pumped.

The use of the packers 32 and 32', etc. will not interfere with the insertion of the device into 15 the well. The packer will be in collapsed position as the device is inserted downwardly and will only be expanded to close against the strainer when fluid is pumped downwardly from above to accomplish this action. 20

By the use of this device the pump may be maintained in operation for periods materially longer than would otherwise be possible. The well may be kept clean and the flow of the producing fluid into the well may be continued for 25 a much longer period than the flow could be maintained at other times where it would be materially cut off through closure of the strainer openings.

What is claimed is:

1. In combination, a well strainer, a pump barrel therein, a plunger reciprocable in said barrel, a skirt secured at its upper end to said barrel and spaced from said barrel below said upper end, a packer between the lower end of 35 said skirt and said strainer, there being an opening in said barrel adjacent the upper end of said skirt to allow the passage of fluid from beneath said skirt to said pump barrel.

2. In combination, a well strainer, a pump barrel 40 therein, a plunger reciprocable in said barrel, a skirt secured at its upper end to said barrel and spaced from said barrel below said upper end, a packer adapted to be expanded by fluid pressure from above to close the space between 45 said skirt and said strainer, there being an opening in said barrel adjacent the upper end of said skirt to allow the passage of fluid from beneath said skirt to said pump barrel.

3. A pump tubing, a pump plunger reciprocable 50 therein, a perforated pipe spaced outside said tubing, a skirt secured to said tubing and flared downwardly, a valve controlled partition within said skirt, there being openings from within said skirt to said tubing above said valve, and means 55 to close the space between the lower end of said skirt and said pipe.

4. A pump tubing, a pump plunger reciprocable 60 therein, a perforated pipe spaced outside said tubing, a skirt secured to said tubing, and flared downwardly, a partition between said skirt and said tubing, there being openings in said tubing above said partition, passages in said partition, a valve closing the passage of fluid 65 downwardly through said passages, and means to close the space between the lower end of said skirt and said pipe.

5. A pump tubing, a plunger reciprocable 70 therein, a strainer spaced outside said tubing, said tubing having openings therein above said plunger, a skirt secured on said tubing above 75 said openings and extending downwardly spaced from said tubing, and means responsive to fluid pressure from above to seal the lower end of said skirt with said strainer. 75

6. A pump tubing, a plunger reciprocable therein, a strainer spaced outside said tubing, said tubing having openings therein above said plunger, a skirt secured on said tubing above said openings and extending downwardly spaced from said tubing, and means responsive to fluid pres-

sure from above to seal the lower end of said skirt with said strainer, and means between said skirt and said tubing to prevent the passage of fluid downwardly therethrough.

5
